UNITED STATES PATENT OFFICE.

HERMAN C. MAISE, OF SPRINGFIELD, MASSACHUSETTS, ASSIGNOR TO SPRINGFIELD BODY CORPORATION OF NEW YORK, OF SPRINGFIELD, MASSACHUSETTS, A CORPORATION OF NEW YORK.

HINGE FOR VEHICLE-BODIES.

1,251,550.

Specification of Letters Patent. Patented Jan. 1, 1918.

Application filed August 23, 1916. Serial No. 118,416.

To all whom it may concern:

Be it known that I, HERMAN C. MAISE, a citizen of the United States, and a resident of Springfield, in the county of Hampden 5 and State of Massachusetts, have invented certain new and useful Improvements in Hinges for Vehicle-Bodies, of which the following is a description.

My invention relates to hinges, and particularly to hinges adapted for use in connection with convertible automobile or carriage bodies.

In the patent to Hinsdale Smith, No. 1,570,571, Feb. 8, 1916, there is shown and described a convertible body having a swinging door provided with a window hingedly connected to the top edge thereof, the arrangement being such that the window may be swung up to form a continuation of the door 20 when it is desired to convert the vehicle into a closed car, and may be swung down alongside the door when it is desired to reconvert the vehicle into an open car. When the vehicle body is in the closed condition there 25 is a window stop located above the door opening, against which the top edge of the hinged window abuts when the door is closed. The hinges connecting the window and door are illustrated as being provided 30 with spring means for normally holding the window at a slight inclination to the door so that the top of the window will contact with the window stop before the door has been completely closed. The complete closing 35 of the door will therefore cause a slight swinging movement of the window relative to the door so as to force it into substantial alignment therewith and produce a tightening of the lower edge of the window, against 40 the top of the door, so that rattling is prevented and dust and moisture are effectively excluded.

The hinges illustrated in the said Smith patent, for connecting the door and window 45 in the manner above described, are similar to the hinge described and claimed in the patent to Hinsdale Smith, No. 1,570,569, Feb. 8, 1916. This hinge includes a beveled

locking member pivoted to one or the attachment members and adapted to be held 50 by means of a spring in a beveled recess formed in the other attachment member.

In carrying out the invention of the first mentioned Smith patent, this hinge is so arranged that the male locking member is 55 fully seated in the recess when the window is slightly inclined with respect to the door, and thus tends to retain the window in such slightly inclined position. When, however, the window is forced into substantial alignment with the door by the complete closing 60 of the door as above described, the locking member of the hinge is cammed partially out of the recess.

Furthermore, in carrying out the invention of either of the Smith patents, the window is supported by two hinges, the door attachment members of which are attached to the vertical members of the frame of the door. These hinges are separate and not 70 interconnected with one another, except through the window frame, and it is therefore necessary, in order to secure alignment 75 of the frame surrounding the window, with the door, that the greatest care be exercised in positioning the hinges. It is also impossible to secure an equal tension upon both 80 hinges unless they are accurately disposed with respect to one another. When they are not so accurately disposed, there results an unequal resistance to movement at the opposite ends of the window frame.

In the Smith patents referred to, there exists no means of varying the normal upright position of the window without moving both hinges to a different position, which is impractical where the hinges have been covered by upholstery, etc.

Some of the objects of my present invention are to provide a unitary structure upon 85 which are carried all of the operative parts of the hinge mechanism which may be easily inserted in or removed from the door as a unit; to provide means whereby the spring-pressed locking member is maintained in the 90 same relation to the member with which it

coöperates when the window is in its slightly inclined position and when it is in alignment with the door; and to provide simple means whereby the normal inclination of the window to the door may be readily adjusted, when necessary, to compensate for any displacement of the parts of the vehicle body resulting from wear.

Further objects of my invention will appear more fully hereinafter.

In the drawings:

Figure 1 is a fragmentary front view showing one embodiment of my improved hinge employed to connect a vehicle body and window;

Fig. 2 is a longitudinal sectional view taken on the line 2—2 of Fig. 1;

Fig. 3 is a fragmentary front view showing a modification of my improved hinge; and

Fig. 4 is a section thereof taken on the line 4—4 of Fig. 3.

In the drawings, 10 designates a plate, preferably of metal, which constitutes the base to which the various members of the hinge mechanism are attached. This plate forms a part of the door and may take the place of the usual cross member at the top of the door. In Figs. 1 and 3, somewhat less than half of the plate is illustrated, but it will be understood that the opposite end of the plate is similar to that illustrated, except that the parts mounted thereon are reversed in position.

It will be evident that all of the parts of the hinge mechanism are assembled upon the plate in their proper relative positions, and the difficulties of manufacture thus greatly avoided, it being merely necessary to attach the plate to the door in order to attach all of the hinge mechanism in its proper position. Furthermore, in case of repair, the plate and the mechanism it carries may be easily removed.

I shall now describe the manner in which the mechanism is attached to the plate:

The plate 10 carries a vertical flange 11 at each end, provided with an aperture 12 to receive one end of the pivot rod 13 of the hinge. The other end of this rod 13 is supported by the apertured boss 14. Interposed between the flange 11 and the boss 14 and mounted on the rod 13 is the other attachment member 15, the upper portion 16 of which is attached to the sash of the window 17, as shown in the drawing.

In order to retain the pivoted window in its raised or lowered position, I provide a locking member 18 which is pivoted at its lower end to the stud 19^a, which is mounted in the plate member 10. The upper end of member 18 is beveled as shown at 19 and is adapted to be received in the beveled recess 20 formed in the attachment member 15,

The upper end of member 18 is also provided with an aperture 21 through which the rod 13 passes, as indicated in the drawings. Intermediate its length, member 18 is provided with another aperture 22 through which passes the rod 23 which is supported by flange 11 and boss 24 formed upon or secured to plate 10. Surrounding rod 23 and interposed between boss 24 and member 18 is the compression spring 25 which tends to force member 18 about its pivot 19^a to cause the bevel 19 formed upon the upper end of member 18 to be forced into the recess 20 formed in the lower end of member 15, and thus normally maintain the attachment members in such a position as to hold the window upright above the door, or, if the window be swung to its lowermost position, to hold the window alongside of the inside of the door. It will be understood that when the window is completely closed down, the upper end 19 of the locking member 18 will again come into alignment with the recess 20 and will be forced therein by the spring 25 to retain the attachment members in their new relative positions. The aperture 21 in locking member 18 is enlarged, as indicated in Figs. 1 and 3, to permit rotation of the locking member about its pivot 19^a and the adjustment of member 18, as will be explained hereinafter.

In the modification illustrated in Figs. 1 and 2, a spring 26 is inserted between the lowermost end of the locking member 18, and the plate member 10; and the screw stud 19^a, upon which the locking member 18 is pivoted, is loosely mounted in the plate member 10. This method of pivoting the lower end of the locking member 18 permits said member to have a slight pivotal movement about the rod 13. It will be evident that by screwing up or backing off the screw stud 19^a the normal position of the window with respect to the door may be varied by causing the locking member 18 to pivot slightly about the rod 13, and that if the window sash is so adjusted that its upper edge abuts against its stop slightly in advance of the closing of the door, the window sash will be moved from the full line position to the dotted line position shown in Fig. 2 upon the complete closing of the door. This movement effects a close joint between the upper edge of the window sash and the door without affecting the position of the end 19 of the locking member 18 with respect to the recess 20.

Thus the cammed surfaces always remain in full engagement and are not moved over one another by the closure of the door. This produces a more positive engagement of the window sash with its stops and does not involve any wear of the cammed surfaces.

The aperture 22 in member 18 through which the rod 23 passes is of sufficient size

to permit the necessary pivotal movement of the member 18 about the rod 13.

In the modification shown in Figs. 3 and 4, I dispense with the spring 26 and attach the lower end of the locking member 18 to the plate 10 by means of screw stud 19^a. If desired, the screw stud may be held against movement into and out of the plate 10 by means of pin 27 which engages in annular slot 28 formed in the screw. It is evident that I may thus adjust the normal position of the window sash by screwing up or backing off screw stud 19^a, as in the modification described above.

If desired, the lower end of the locking member 18 may be made in such form that it will spring slightly upon the closure of the door if the window sash be adjusted to such a position that it will come against the stops slightly in advance of the closure of the door.

I have shown in Figs. 3 and 4 additional adjusting means for adjusting the normal position of the window sash, said means comprising a screw plug 28^a which enters a screw-threaded recess formed in the lower side of the window sash. By screwing up or backing off screw plug 28^a the normal position of the window frame may be adjusted, as shown in Figs. 3 and 4. In order to lock screw stud 28^a in place, a set screw 29 located concentrically to screw stud 28^a may be tightened until it is forced against the end of the screw-threaded recess. A very simple adjustment of the normal position of the window sash is thus provided which can be used either independently of or in conjunction with the adjustment provided at the lower end of locking member 18.

While I have shown and described my improved hinge as applied to a vehicle door and window, it is obvious that it may be used for any other purpose wherein it is found desirable to normally lock the hinged members in a predetermined position, but wherein a slight adjustment of such position must be provided without disturbing the locking means.

I do not wish to limit myself to the particular form or application of my invention disclosed herein, since obviously many changes may be made without departing from the spirit of my invention.

What I claim is:

1. In a device of the kind described, a plate, an attachment member having a cammed surface formed thereon pivotally mounted upon said plate, a locking member having a cammed surface formed thereon also pivotally mounted upon said plate and adapted to coöperate with said attaching member, and means connected to the plate and locking member for varying the angular relation of the plate and locking member.

2. In a device of the kind described, an attachment member having a cammed surface formed thereon, a pivot mounted upon said plate and passing through said member, a locking member through which said pivot passes pivotally mounted upon said plate, and means for varying the angular position of the locking member and attaching member upon said pivot.

3. A hinge comprising a pair of pivotally connected attachment members, a locking member mounted upon one of said attachment members to coöperate with the other and adapted to normally maintain said attachment members in a predetermined angular relation to each other, and means to maintain the position of the locking member with respect to the attachment member with which it coöperates during slight variations in the predetermined angular relation of the attachment members.

4. A locking hinge comprising a pair of pivotally connected attachment members, a locking member adapted to coöperate with one of said attachment members to normally maintain said attachment members in a predetermined angular relation to each other, and means for adjusting the locking member to determine the normal angular relation of said attachment members.

5. A locking hinge comprising a pair of pivotally connecting attachment members, a locking member mounted upon one of said attachment members and adapted to coöperate with the other to maintain said attachment members in a predetermined angular relation with each other, a spring to force said locking member into engagement with its coöperating attachment member, and means for adjusting the position of the locking member to determine the normal angular relation of said attachment members.

6. A locking hinge comprising an attachment member provided with a recess, a second attachment member pivoted to said first attachment member, a locking member movable toward and from said first attachment member and also movable angularly therewith, means for normally retaining the locking member in said recess, and spring means for normally restraining said angular movement of said locking member, whereby the attachment members are normally maintained in predetermined angular relation to each other by said locking member, but may be moved therefrom against the action of said spring means without affecting the position of the locking member with respect to said recess.

7. A locking hinge comprising an attachment member provided with a recess, a second attachment member pivoted to said first attachment member, a locking member adapted to be yieldingly retained in said

recess to normally maintain the attachment members in a predetermined angular relation to each other, said recess and locking member being beveled so that forcible movement of one attachment member with respect to the other will normally cam the locking member out of the recess, and means

whereby the attachment members may be moved slightly from this predetermined angular relation without effecting any camming action between the recess and locking member. 13

HERMAN C. MAISE.
